UNITED STATES PATENT OFFICE.

JAMES MAHEDY, OF KELLERTON, IOWA.

HEATING-DRUM.

SPECIFICATION forming part of Letters Patent No. 662,364, dated November 20, 1900.

Application filed May 10, 1900. Serial No. 16,171. (No model.)

To all whom it may concern:

Be it known that I, JAMES MAHEDY, a citizen of the United States, residing at Kellerton, in the county of Ringgold and State of Iowa, have invented certain new and useful Improvements in Heating-Drums; and I do declare the following to be a full, clear, and exact description of the invention, such as will enable others skilled in the art to which it appertains to make and use the same.

The invention relates to heating-drums, and more particularly to that class of heating-drums adapted to be connected up with the smoke-pipe of a stove and be located in the same room as the stove or in a distant room.

The object of the invention is to provide a device of this character which shall be simple of construction, durable in use, and comparatively inexpensive of production, special provision being made whereby the direction of the circulation of the products of combustion may be reversed at will for the purpose of dislodging or preventing the accumulation of soot or the like within the heating-drum.

With this object in view the invention consists in certain features of construction and combination of parts which will be hereinafter fully set forth.

In the accompanying drawings, Figure 1 is an elevation of my improved heating-drum. Fig. 2 is a vertical sectional view, and Fig. 3 is a similar view showing the valves set to reverse the position of circulation of the products of combustion.

Referring to the drawings, 1 denotes a smoke or soot box, one end of which is provided with a removable cap 2 to enable a tool or scraper to be inserted for the purpose of withdrawing the accumulations.

2' denotes a hood, and 3 and 4 denote heat-radiating tubes, which establish a communication between said hood and smoke-box. The hood is provided with a transverse partition 5, below which is an inlet-orifice 6, which communicates with the smoke-pipe and above which is an outlet-orifice 7, which communicates with the chimney. The partition is provided with two openings *a b*, either of which is adapted to be closed by a valve *c*, operated by a rod *d*.

e and *f* denote sleeves having a vertical sliding movement in the heat-radiating tubes 3 and 4 and are adapted to project up through the lower compartment in the hood and register with either one of the apertures *a b*. An operating rod or pin *g* extends laterally from each of these sleeves through a vertical slot in the heat-radiating tubes 3 and 4, and when either sleeve is elevated the pin or rod is turned into the transverse or horizontal extensions at the upper end of the slot, thus holding the sleeve in its elevated position.

As shown in Fig. 2, the products of combustion from the stove enters the hood below its partition, passes downward through the tube 4, through the smoke-box, and up through the tube 3 and the hole *a* in the partition into the upper part of the hood, from whence it escapes into the chimney. In this position the valve *c* is over the hole *b*. After the device has been used some little time it is well to reverse the direction of circulation in order to remove any accumulations of soot and ashes, and this is readily done by reversing the position of the sleeves *e* and *f* and the valve *c*, as shown in Fig. 3.

From the foregoing description, taken in connection with the accompanying drawings, the construction, operation, and advantages of my improved heating-drum will be readily apparent without requiring an extended explanation. It will be seen that the device is simple of construction, that said construction permits of its manufacture at small cost, and that it is exceedingly well adapted for the purpose for which it is designed.

Various changes in the form, proportion, and the minor details of construction may be resorted to without departing from the principle or sacrificing any of the advantages of this invention.

Having thus fully described my invention, what is claimed as new, and desired to be secured by Letters Patent, is—

In a heating-drum, the combination with a smoke-box and the hood provided with a partition having openings therein, of tubes connecting the smoke-box with the hood and registering with the openings in the partition, an inlet to the hood arranged below the

partition, an outlet from the hood arranged above the partition, a valve for closing either one of said openings in the partition, and vertically-movable sleeves located within the tubes and adapted to be moved alternately into engagement with the partition and in communication with the holes therein, substantially as set forth.

In testimony whereof I have hereunto set my hand in presence of two subscribing witnesses.

JAMES MAHEDY.
